UNITED STATES PATENT OFFICE.

POWHATAN A. WEBB, OF ATLANTA, GEORGIA.

TOBACCO-SMOKING PIPE.

Application filed June 4, 1926. Serial No. 113,789.

This invention relates to tobacco smoking pipes and particularly to a novel form of such pipes.

It is a general object of the present invention to provide a novel and improved tobacco smoking pipe.

More particularly it is an object of the invention to provide a pipe in which air is admitted and admixed with the smoke, at 10 the bottom of the bowl, for the purpose of cooling the same.

Another object of the present invention consists in the provision of a pipe, having the main bore of the bowl provided with 15 a flat bottom and a laterally extending groove, together with passages through the walls of the bowl connecting the groove with the top surface of the bowl and a valve for regulating the amount of air passing through these passages.

Other and further objects will be more apparent from a consideration of the following specification and accompanying drawing wherein is disclosed a single exemplary embodiment of the invention with the understanding, however, that various changes may be made therein without departing from the spirit of the invention or the scope of the attached claims.

30 In said drawing:

Fig. 1 is a longitudinal vertical section through a pipe constructed according to the present invention; and

Fig. 2 is a plan view of the same.

The present invention contemplates the provision of a pipe following along the general lines of those in common use and provided with a bowl 10 having an integral stummel 11 formed of wood or other suitable material. The bowl is provided with the usual tobacco receiving compartment or bore 12 into which leads the smoke passage 13 in the stummel. This passage 13 is continued at 14 in the bit or stem 15 formed of 40 vulcanite or any of the various materials used for this purpose.

The bottom of the bore 12 is preferably flat as shown at 16, and just above the bottom and contiguous therewith is the lateral groove 17 extending circumferentially around the bottom of the bore. This groove extends laterally approximately $\frac{1}{8}$ inch and has a vertical depth of about $\frac{1}{16}$ inch. Its purpose is to provide an annular compartment surrounding the bottom of the bore and into which but little tobacco is received

owing to its narrowness. The bore 13 in the stummel enters this groove 17 whereby suction, during the process of smoking, is applied substantially equally around the periphery of the bore of the bowl to thus cause the tobacco to burn more evenly. It also serves to eliminate hot spots which cause excessive heating not only of the bowl of the pipe but of the smoke.

A number of smokers are troubled by burning of the tongue from the heat of the smoke passing through the passage 14 in the stem and impinging directly on the tongue. In order to cool the smoke and to some extent dilute the same, means are provided for admitting a regulated quantity of air into the smoke before it passes into the bore of the stummel. These means comprise a plurality of substantially vertical passages or bores 18 passing through the walls of the bowl and substantially parallel to the walls of the tobacco compartment. These passages are so positioned that their lower ends open through the upper wall 19 of the groove 17 and are thus not subject to clogging by tobacco packed in the bowl.

The top of the bowl is preferably flat and the passages 18 open into this flat annular surface and are thus in communication with the atmosphere so that, during the smoking of the pipe, air is drawn through the passages as well as through the tobacco, the smoke and air commingling in the groove 17 before being drawn into the passage 13 in the stummel. Preferably three passages 18 are provided, spaced as shown in Fig. 2 with one directly opposite the smoke passage 13 and the other two at 120° intervals therefrom. They are thus sufficiently spaced from the passage 13 to prevent the drawing of substantially pure air through the smoke passage.

In order to prevent tobacco entering the air passages 18 when the pipe is being filled and to provide a good draft when lighting the pipe and at other times when desired, means are provided for closing off the upper ends of these passages 18. Such means comprises an annular plate 20 of aluminum or any other suitable metal or material provided with the circumferential slots 21 through which pass the screws 22, the lower ends of which are engaged in the material of the bowl. The screws are provided with enlarged heads 23 or with washers 24 to retain the metal plate 20 in position and yet to al-

low it to be rotated. The desired amount of friction, to hold the plate in any adjusted position, is provided by tightening or loosening the screws. The plate 20 is provided 5 with three apertures 25 positioned so that when the plate is turned to its maximum in one direction these apertures register with the openings of the air passages 18 to allow the air to pass freely therethrough. At the 10 other extreme position the openings 25 are out of register with the tops of the air passages and the solid part of the plate completely closes off the same. At intermediate positions varying amounts of air are 15 allowed to pass into the passages in accordance with the amount that the ends of the same are uncovered by the openings 25.

On filling and lighting the pipe, the passages 18 are preferably closed by the plate 20 but after the tobacco is burning well they are opened to any degree according to the desire of the smoker and the smoke may thus be cooled sufficiently to prevent burning of the tongue. The construction of the pipe is 25 such that the tobacco can be burned clear to the bottom, an excellent draft being provided for that purpose by the groove 17. It has been found from experience that the air passing through the passages 18 serves to 30 evaporate moisture in the bottom of the bowl caused by condensation and saliva which runs in through the stem, so that there is no damp or soggy tobacco left at the end of the smoke and all of the tobacco 35 can therefore be consumed. This materially improves the odor of the pipe and of the smoke.

Having thus described the invention, what is claimed as new and desired to be secured 40 by Letters Patent is:

1. In a tobacco pipe in combination a bowl and a stummel, said bowl having a tobacco compartment enlarged in diameter at the bottom, said stummel having a smoke 45 passage entering said enlargement of the tobacco compartment, said bowl being provided with a passage substantially parallel to the wall of the tobacco compartment and connecting said enlargement to atmosphere

at the top surface of said bowl and an adjustable valve on said top surface to regulate the flow of air into said enlargement. 50

2. In a tobacco pipe in combination a bowl having a flat top and a tobacco receiving bore, said bore being provided with a lateral groove at the bottom thereof, a stummel having a smoke passage leading from said groove, said bowl being provided with an air passage parallel to the wall of the tobacco bore and connecting said groove to the 55 flat top, an annulus rotatably mounted on said flat top and provided with a hole which can be brought into and out of registration with said air passage for the purpose described. 60

3. In a tobacco pipe, in combination a bowl having a flat top and a tobacco receiving bore, said bore being provided with a flat bottom and a lateral groove contiguous to said bottom, a stummel having a smoke 70 passage leading from said groove, said bowl being provided with a plurality of air passages leading from said flat top to said groove, an annulus on said top having slots and holes therein, headed screws passing 75 through said slots into said bowl to rotatively secure said annulus in position, said holes being adapted to be moved into and out of registry with said air passages.

4. In a tobacco pipe, in combination a bowl having a flat top and a tobacco receiving bore, said bore being provided with a flat bottom and a lateral groove contiguous to said bottom, a stummel having a smoke 80 passage leading from said groove, said bowl being provided with a plurality of air passages leading from said flat top to said groove, an annulus on said top having slots and holes therein, headed screws passing 85 through said slots into said bowl to rotatively secure said annulus in position, said holes being adapted to be moved into and out of registry with said air passages, said air passages entering the groove at material distances from the smoke passage. 90

In testimony whereof I hereunto affix my signature.
